STORAGE BATTERY CASE

Wilford Benson Burkett, Palisades, and Anthony Joseph Carsello, Rolling Hills, Calif., assignors to McCulloch Corporation, Los Angeles, Calif.

Filed Aug. 12, 1971, Ser. No. 171,405

Term of patent 14 years

Int. Cl. D13—02

U.S. Cl. D26—6

FIG. 1

FIG. 2

FIG. 3

FIG. 4

FIG.5

FIG.6

FIG. 7

FIG. 1 is a perspective view of a storage battery case designed in accordance with a preferred embodiment;

FIG. 2 is an end view of the storage battery case shown in FIG. 1, illustrating a side opposite to that shown in FIG. 1;

FIG. 3 is a front elevational view of the storage battery case shown in FIG. 1;

FIG. 4 is a top plan view of the storage battery case shown in FIG. 1;

FIG. 5 is a rear side elevational view of the storage battery case shown in FIG. 1, this side being opposite to that shown in FIGS. 1 and 3;

FIG. 6 is a bottom plan view of the storage battery case shown in FIG. 1; and

FIG. 7 provides a modified view of the FIG. 1 storage battery case with a lid thereof partially raised.

We claim:

The ornamental design for a storage battery case, substantially as shown and described.
